COMB

Michael C. Demis and John W. Killinger,
Napa, Calif.

Application April 28, 1950, Serial No. 9,558

Term of patent 14 years

(Cl. D86—8)

To all whom it may concern:

Be it known that we, John W. Killinger, a citizen of the United States, and a resident of the city of Napa, Napa County, State of California, and Michael C. Demis, a resident of the city of Napa, Napa County, State of California, have invented a new, original, and ornamental Design for a Comb, of which the following is a specification, reference being had to the accompanying drawing, forming a part hereof, and wherein

Figures 3, 4 and 5 are, respectively, sections taken upon the indicated section lines 3, 4 and 5 of Figure 1.

We claim:

The ornamental design for a comb, substantially as shown.

MICHAEL C. DEMIS.
JOHN W. KILLINGER.
